UNITED STATES PATENT OFFICE

EUGENE A. SCHENCK, OF KANSAS CITY, KANSAS, ASSIGNOR OF ONE-HALF TO DAVID E. JUSTUS, OF KANSAS CITY, MISSOURI

STEAM OR HOT-WATER BOILER

Application filed March 15, 1926. Serial No. 94,763.

My invention relates to improvements in steam or hot water boilers.

The object of my invention is to provide a novel steam or hot water boiler which is simple, cheap to make, durable, not liable to get out of order, which is economical of fuel, and which is efficient in operation.

My invention provides further novel means for supporting a sectional boiler, which affords additional heating means, improves the circulation of the water in the system.

The novel features of my invention are hereinafter fully described and claimed.

In the accompanying drawings, which illustrate the preferred embodiment of my invention,

Fig. 1 is a view, partly in front elevation and partly in vertical section of my improved water heating apparatus.

Fig. 2 is a perspective view of one of the baffle plates or bars.

Fig. 3 is a vertical sectional view on the line 3—3 of Fig. 1.

Fig. 4 is a top view of one of the boiler sections.

Fig. 5 is an enlarged fragmental vertical sectional view of a part of the boiler.

Fig. 6 is a cross section on the line 6—6 of Fig. 5.

Similar reference characters designate similar parts in the different views.

1 designates a casing, which may be of any desired form or material suitable for the purpose, and which is shown as being brick laid against a lining of steel 2, the inner side of which is covered by asbestos lining material 3. The front of the casing has an opening 4 normally closed by two doors 5 and 6 hinged to each other one above the other and having in their adjacent edges respectively notches forming holes 7 through which oil or gas pipes, not shown, may be inserted for supplying fuel to the fire box 8 with which the opening 4 communicates.

Provided in one side of the casing 1, may also be openings 9 and 10, one above the other, and communicating with the fire box 8, and normally respectively closed by doors 11 and 12.

This side of the casing 1 may also be pro-

vided with a large opening 13, normally closed by a door 14. This opening 13 permits access to the sectional boiler which is within the casing 1.

The top of the casing 1 has a central vertical smoke pipe 15, which is spaced from and discharges into the lower flaring end of a flue pipe 16, which communicates with a suitable flue, not shown.

The tubular boiler comprises a plurality of sections disposed one above the other in the casing 1, and each section comprising two horizontal headers 17 connected with each other by tubes 18. Each header 17 on its under side has a central inlet 19, and in its upper side a central outlet 20.

The lowermost and uppermost sections have horizontal tubes 18, Fig. 1, while the tubes 18 of the intermediate sections are inclined and arranged in zig-zag manner adjacent sections having their tubes 18 inclined in opposite directions, that is alternately to the right and left.

Short nipples 21, preferably push nipples, forming conductors for water or steam connect the outlets 20 with inlets 19 of those headers which are close together, and longer nipples 22 connect those headers which are farther apart.

As shown in Fig. 5, the outlets 20 of the uppermost headers 17, and the inlets 19 of the lowermost headers 17 have respectively seated in them yokes 23. Two vertical threaded rods 24 respectively connect the upper yokes with the lower yokes 23, said rods extending through the nipples 21 and 22 adjacent thereto. Nuts 25 on the rods 24 bear upon the yokes 23 for holding the sections and nipples tightly together.

For supporting the boiler, two vertical stand pipes are provided each comprising a vertical tube 26 having its upper end mounted in the adjacent inlet 19 of the lowermost section, the lower end of the tube being mounted in a T 27, the lower end of which is mounted on and closed by a foot member 28 which rests on the floor of the casing 1 in the fire box 8.

Connected respectively to the T's 27 are two water return pipes or conductors 29,

which lead from opposite sides respectively of the casing 1 to the radiators, not shown of the heating system.

5 Two steam or hot water discharge pipes or conductors 30 are respectively connected to the outlets 20 of the uppermost section. The pipes 30 connect with the aforesaid radiators.

10 Two horizontal pipes 31 respectively connect the two return pipes 29 with the headers 17 of the lowermost section, the latter serving as a crown sheet for the fire box.

15 A conductor 32 connecting one of the return pipes 29 and one of the pipes 30 includes a water gauge 33, by which the height of the water in the boiler may be ascertained.

20 For extending the travel of the gaseous products of combustion upwardly through the sections between the tubes 18, I provide baffle members comprising plates 34, one of which is shown in Fig. 2, which rest upon and are disposed between and wholly supported by the tubes 18 which are adjacent to each other in each section. Said baffle plates extend from the lower header of each intermediate section toward, but are spaced from the upper header of each intermediate inclined section. Baffle plates 34 need not be provided on the uppermost and lowermost sections.

30 As shown in Fig. 1, the baffle plates 34 will be disposed alternately on the right and left sides of the boiler, so that the gaseous products in passing from the fire box 8 will take a 35 sinuous path, as indicated by the arrows, Fig. 1.

40 By having the uppermost and lowermost sections horizontal the water entering the boiler and discharged therefrom will be divided into equal quantities passing respectively into the pipes 30. By mounting the stand pipes, which support the boiler, in the fire box, the water passing therethrough will be heated, and by providing the connecting pipes 31 with the return pipes 29 and the headers of the lowermost headers, the circulation through the boiler and system is accelerated.

50 The disposition of the inclined tubes of the intermediate sections assists in a natural way the upward movement of the water therein and of the heated gaseous products at their outer sides.

55 In the operation of the apparatus, the cold water enters the stand pipes from the return pipes 29, cooling the stand pipes sufficiently to keep them from being burned out, and is heated thereby. The water then enters the lowermost section, and passes from the header outlets by the adjacent nipples 21 and 22 into the inclined intermediate section next above, and from thence through the other sections to the uppermost section from which the steam or hot water is discharged into the 60 pipes 30.

I do not limit my invention to the structure shown and described, as many modifications, within the scope of the appended claim, may be made without departing from the spirit of my invention.

70 What I claim is:—

In a boiler, a casing having a fire box and a smoke outlet, boiler sections disposed one above the other in said casing, the lowermost section being connected interiorly adjacent to its opposite ends with the section next above, two discharge pipes connected respectively to the uppermost section adjacent to its ends, two stand pipes in said fire box respectively communicating with said lowermost section adjacent to the ends thereof, and two return pipes each having two branches, the branches of one return pipe connecting respectively with one end of said lowermost section and with the adjacent stand pipe adjacent to the bottom end thereof, and the branches of the other return pipe connecting respectively with the other end of said lowermost section and with the other stand pipe adjacent to the lower end of the latter.

75 80 85 90 In testimony whereof I have signed my name to this specification.

EUGENE A. SCHENCK.
